UNITED STATES PATENT OFFICE.

FRANK H. DAVIS, OF BROOKLYN, NEW YORK.

FEEDER FOR STAMPING-PRESSES.

1,210,278.

Specification of Letters Patent. Patented Dec. 26, 1916.

Application filed February 6, 1915. Serial No. 6,647.

To all whom it may concern:

Be it known that I, FRANK H. DAVIS, a citizen of the United States, residing at Brooklyn, in the county of Kings and State 5 of New York, have invented new and useful Improvements in Feeders for Stamping-Presses, of which the following is a specification.

This invention relates to feeding mechanisms for stamping presses of that kind 10 particularly designed and adapted for applying gold or other metallic leaf to surfaces to be ornamented.

One object of the invention is to provide 15 a feeding mechanism by means of which a ribbon or strip bearing the gold leaf may be intermittently fed forward to bring new portions of the gold leaf into position beneath the die for the successive printing or 20 stamping operations.

A further object of the invention is to provide means whereby the ribbon may be positively fed forward and its extent of feed motion regulated and controlled in a ready, 25 convenient, and efficient manner.

A further object of the invention is to provide a feeding mechanism which may be adjusted to shift the strip into and out of registry with the die.

30 A further object of the invention is to provide a feeding mechanism of the character described which may be applied to any ordinary type of stamping press employing a die carrying heat embodying means for heating the stamping die.

The invention consists of certain novel features of construction and arrangement of parts which will be fully understood by reference to the description of the drawings 40 and to the claims hereinafter given.

Of the drawings: Figure 1 represents a rear elevation of a device embodying the principles of the present invention, said device being shown in connection with the 45 essential parts of a stamping press, the remainder of the press being omitted. Fig. 2 represents a vertical longitudinal section of the same. Fig. 3 represents a sectional plan view of the same. Fig. 4 represents a detail section of the same, the cutting plane being on line 4-4 of Fig. 3. Fig. 5 represents a detail section of the same, the cutting plane being on line 5-5 of Fig. 3. Fig. 6 represents a detail section of the same, the 50 cutting plane being on line 6-6 of Fig. 3. Fig. 7 represents a detail section showing

a modification in the strip feeding means of the feeding mechanism. Fig. 8 represents a front elevation, partly in section, showing a modified form of feeding mechanism. Fig. 9 represents a sectional view of the same, showing the feeding mechanism in printing or stamping position, and Fig. 10 represents a similar view showing the feeding mechanism adjusted to shift the ribbon 65 strip out of printing position.

Similar characters designate like parts throughout the several figures of the drawings.

In the drawings, 1 designates the plunger or removable die head of the stamping press, 2 the die, 3 the tube or pipe for supplying gas or other fuel whereby the die may be heated, and 4 the platen upon which may be placed an article 5 which is to be stamped or printed, in order that it may receive the impression from the die. In practice, the die is heated and on its downward movement comes in contact with the metallic ribbon strip or leaf 6, whereby portions of the metallic film 7 carried by said strip are impressed against the article 5.

The invention is particularly designed for supporting and feeding a metallic ribbon strip of the character disclosed in a prior 35 Patent, No. 1,124,114, dated January 5, 1915, for metallic leaf ribbon, and in another Patent, No. 1,124,869, dated January 12, 1915, for art or method of gold leafing surfaces. The ribbon disclosed in the before-mentioned patents consists of a carrier strip of a paper or other suitable material in roll form, to one surface of which is secured the gold or other metallic leaf, the outer face of which is coated with a sizing adapted to 95 become tacky when subjected to the pressure of the characters upon the heated die. By this means the particles of gold beneath the characters on the die are transferred from the strip to the surface to be ornamented, and secured to such surface by pressure and the adhesive action of the size, the work being burnished or glossed to the desired degree.

As illustrated the ribbon strip 6 is preferably wound in roll form upon a roll 8 which is journaled for rotation upon a bracket 9, removably fastened to a bar 10 by a set screw 11 or other suitable fastening means. The bar 10 forms a cross bar at one end of an oblong rectangular frame 12, which includes a pair of longitudinal bars 13 and

11 connected at one end by the bar 10, while a cross bar 15 connects the other ends of the bars 13 and 14. A pair of intermediate cross bars 16 and 16' are also interposed between the bars 13 and 14. The bars 13 and 14 have depressed portions 17, forming with the bars 16 and 16' a collar to embrace the head of the die 2, the bars 16 and 16' being provided with set screws 17', whereby the feeder frame may be removably clamped to the die 2.

The ribbon strip is adjusted for use by extending the free end of the strip longitudinally between and parallel with the longitudinal bars 13, 14 of the frame, beneath the cross bars 10, 15, 16 and 16' and directly under the die 2 and attaching the extremity of such end of the strip to a feed drum or roller 19. For the purpose of accurately guiding the strip when in normal or stamping position, a notched gage or guide plate 20 may be provided upon the front cross bar 15, which plate is shown as provided with a transverse slot 21 through which extends a clamping screw 22 engaging a thread opening in said cross bar 15, whereby the gage may be adjusted laterally to direct the line of feed of the ribbon as occasion may require in the use of different dies. The gage 20 is also rendered removable so that ribbons and gages of different widths may be employed.

The feed roll or drum 19 shown in the present instance is formed with bearing recesses 23 at its opposite ends, which bearing recesses are of conical form. One of these bearing recesses receives a conical bearing member or boss 24 upon a bracket extension 25 from the side bar 13, while the other bearing recess receives a conical bearing member 26 upon the end of a screw 27 working in a threaded opening in another bracket extension 28 at the front end of the side bar 14, whereby the bearing members may be relatively adjusted to take up wear or to permit of the application and removal of the roll or drum 19, a check nut 29 being provided to secure the screw 27 in adjusted position.

One end of the roll or drum 19 carries a ratchet wheel 30 with which engages a spring actuated pawl or dog 31 carried by a gear member 32 loosely mounted on the drum, which gear meshes with rack teeth 33 upon the forward end of a feed bar 34, the said bar and pawl and ratchet mechanism providing a means whereby the ribbon strip may be intermittently fed forward to successively bring different portions of the ribbon beneath the face of the die, as will be readily understood.

When the ribbon is arranged in operative position, the film side 7 faces downward so that upon the depression of the die it will be brought into contact with the work 5,

the subsequent upward movement of the die raising the strip from the work, allowing the latter to be removed from the platen or left to remain for subsequent treatment and the ribbon to be shifted forward to bring a new portion of the gold leaf in position beneath the die for the succeeding transfer. After the die is raised,

the operator moves the strip forward by shifting the rack bar forwardly by means of a lever or handle 35 attached thereto,

by which movement the dog 31 will be swung forwardly and will engage a tooth of the ratchet wheel and couple the gear 32 to the feed roll or drum 19, thereby caus-

ing this feed motion to be transferred to said drum to shift the ribbon a prescribed degree forwardly. The rack bar 33 on its return motion will rotate the gear 32 with it, the pawl 31, however, in this action

sliding over the tooth of the ratchet wheel which will retain the position to which it has been adjusted. A coiled spring 36 is provided for retracting the rack bar, said spring being fixed at its forward end to a

suitable part of the frame with its rear end suitably connected to an adjustable collar or sleeve 37 mounted on the rack bar and adapted to be fastened in adjusted position by means of a set screw 38, whereby

the spring may be set and tensioned as desired for a proper working action. The rack bar slides through guide members 39,

and upon said bar is a stop collar 40 adjustable longitudinally and provided with a set screw 41 for securing it in adjusted position, said collar being adapted to abut against the rear guide member 39 to limit

the motion of the rack bar toward the rear of the machine, whereby the range of feed motion of said bar may be varied to feed the strip to a greater or less extent forwardly as occasion may demand. In the present instance I have also shown the han-

dle 35 provided with a sleeve which is slidably adjustable on the angular rack bar 33 and adapted to be fixed by a set screw 35', said handle being arranged to abut against the rear guide member 39 to limit the for-

ward motion of the rack bar. It will thus be seen that when the article 5 which is to be embossed or stamped is disposed in place upon the platen 4, the die head or

plunger may be moved downwardly so that the heated die will engage and force the strip against the surface of the article, by

which the size will be fused along the lines of impression and transfer localized portions of the metallic film to the work, by

which a combined stamping, sizing, and polishing or burnishing action is effected.

Upon the die being then raised the strip may be fed forward by the intermittent feed mechanism to bring another portion of the strip beneath the die for the next stamping

130

action. The stop member 40 is so positioned that the portion of the strip 6 previously acted upon by the die 2 will be entirely removed from beneath the said die 5 before the next downward movement thereof. This feeding operation of the strip continues after successive impressions until the strip is entirely unwound from the core or roll 8 and transferred to the roll or drum 10 19, from which latter it may be removed for the recovery of the remainder of the gold adhering thereto. If the circumstances of the case require a greater or less degree of feed motion of the metallic ribbon leaf after 15 each stamping operation, this may be effected by adjusting the parts of the intermittent feed mechanism to vary the extent of feed motion of the strip.

In the structure shown in Fig. 7, the free 20 end of the ribbon leaf instead of being wound directly upon the drum 19' (which is here shown as ribbed or corrugated) is disposed to pass between said drum and a guide roll 19^a driven by friction from the 25 drum 19, the strip passing between said rolls into any suitable receptacle in which it may be stored until it is desired to treat the same for the recovery of the remaining particles of the gold leaf therefrom.

30 In Figs. 8 to 10 inclusive, I have shown a modified form of the feeding mechanism which is structurally the same as that previously described, except that it is made of materially greater width than the die head 35 and its cross bars 16 and 16' slidably engage grooved guide members 42 secured to the die or head 2, so that the feeder frame may be shifted upon the die head in a direction transversely or at right angles to the 40 line of feed of the ribbon leaf. The object of this construction and mode of mounting is to provide for the shifting of the ribbon leaf into and out of the path of movement of the die, or to bring different portions of 45 the leaf beneath the type matter or working face of the die.

When the parts are arranged as shown in Fig. 3, the feeder is in printing or stamping position, with the ribbon leaf arranged 50 directly beneath the die, so that upon the depression of the die a print or impression will be made through the leaf. By thus shifting the feeder laterally of the line of feed of the ribbon leaf, as illustrated in Fig. 55 10, the ribbon may be moved out of register with the face of the die, so that, as may happen in some cases or in doing some classes of work, if the stamped gold is not burnished to the desired degree, the ribbon may be 60 shifted to allow the die to come directly into

contact with the work for a burnishing action. In this operation it will, of course, be understood that the operator will first make an impression upon the work through the ribbon strip, thus transferring the gold leaf, 65 will then shift the ribbon out of register with the die without disturbing the work, and will then bring the die down into engagement with the work. In printing single lines of type or other matter this shifting feeder is also of advantage in enabling different portions of the ribbon to be brought under the die matter by moving the ribbon in a transverse direction to its line of feed, 70 as will be readily understood. The feeder 75 may be held in adjusted position by frictional engagement or other suitable fastening means.

It is believed that the operation and many advantages of this invention will be fully so understood from the foregoing description.

Having thus described my invention, I claim:

1. In a device of the character described, the combination of a support adapted to be secured to the reciprocating die of a stamping press; revoluble rolls mounted upon said support on opposite sides of said die, said rolls carrying a ribbon movable beneath the face of said die; a stop member adjustable on said frame to regulate the amount of movement of said ribbon; a manually controlled member supported by said frame and movable relatively thereto, said movement being limited in one direction by said stop member; and means for rotating one of said rolls by the movement of said manually controlled member.

2. In a device of the character described, the combination of a frame; means disposed at or near the center of the frame for securing the same to a plunger or die; rolls upon the ends of the frame for the extension of the ribbon strip; a ratchet wheel associated with one of said rolls; a dog for actuating said ratchet wheel; a pinion for actuating the dog; a longitudinally movable rack bar for actuating the pinion; an adjustable stop device for regulating and varying the stroke of the rack bar; a retracting spring secured at one end to the frame; and a slidably adjustable connection between the rack bar and the other end of the spring.

In testimony whereof I affix my signature in presence of two witnesses.

FRANK H. DAVIS.
